UNITED STATES PATENT OFFICE.

AUGIE L. HANSEN, OF CHICAGO, ILLINOIS, ASSIGNOR TO JUSTRITE MANUFACTURING COMPANY, OF CHICAGO, ILLINOIS, A CORPORATION OF ILLINOIS.

ACETYLENE-LAMP.

1,303,658.

Specification of Letters Patent. Patented May 13, 1919.

Application filed August 31, 1918. Serial No. 252,148.

To all whom it may concern:

Be it known that I, AUGIE L. HANSEN, a citizen of the United States, residing at Chicago, in the county of Cook and State 5 of Illinois, have invented certain new and useful Improvements in Acetylene-Lamps, of which the following is a description, reference being had to the accompanying drawings, forming part of this specification.

10 My invention relates more particularly to acetylene lamps of the small portable type, and especially to those adapted for use as miners' cap lamps; and it has for its object the simplification of the construction and 15 increase in the efficiency of such lamps; all as hereinafter set forth and more particularly pointed out in the claims.

In the accompanying drawings Figure 1 is a side elevation of a miner's cap lamp 20 embodying my invention, with the carbid chamber of the lamp shown in section, and with a portion of the water reservoir and flanged screw-connection broken away to expose the felt-holder and lower portion of 25 the tubular casing and water tube; Fig. 2 a middle vertical section through the complete lamp axially of the burner and water reservoir; Fig. 3 a side elevation of the tubular casing and inclosed tube; Fig. 4 a 30 side elevation of the casing alone; Fig. 5 a similar view with the casing turned ninety degrees; and Fig. 6 a side elevation of the water tube and rod removed from the casing.

The same letters of reference are employed to represent corresponding parts in the several views.

The miner's cap lamp in which I have shown my invention in the accompanying drawings is of a familiar form and comprises, primarily, a carbid chamber A and a superimposed water reservoir B, with provision for permitting the water to flow in regulated quantities from the water reservoir into the carbid chamber, the gas generated in the latter being burned at the burner tip C. My present invention consists in a novel construction and arrangement of parts for regulating and controlling the flow of water from the water reservoir 45 to the carbid chamber, and for stirring or opening up the slaked carbid in the latter, when necessary or desired, to permit a freer flow of water. These provisions will now be explained.

50 Secured in the top of the water reservoir

B, being soldered therein, is the upper end of a tubular casing D which extends vertically downward through the reservoir, and through the bottom wall of the latter, to which it is also soldered to form a tight 60 joint, and projects downward into the carbid chamber to a point a short distance above its bottom.

In the particular form of lamp in which I have illustrated my invention in the accompanying drawings, the carbid chamber A is detachably secured to the water reservoir by a screw-connection, for which purpose the upper end of the carbid chamber is contracted into a reduced portion or neck 65 a provided with coarse screw threads adapted to engage corresponding threads formed in a socket b secured in the bottom of the reservoir B. A rubber gasket a' surrounding the neck a of the carbid chamber and resting upon the annular shoulder formed by the contraction of the latter, and confined between said shoulder and the flaring flange b' of the lower end of the screw-socket b of the water reservoir, effects a gas-tight joint 70 75 between the carbid chamber and water-reservoir.

The screw-threaded socket b is secured in the bottom of the water reservoir by soldering and projects upwardly therein a short 80 distance above its bottom. The top of the socket is of concavo-convex form, with its convex surface presented downward. The tube D extends centrally through this socket, while also secured therein is the 85 lower end of a curved gas-pipe c whose upper and laterally extending end is secured to the center of the reflector of the lamp and communicates with the burner tip C.

Surrounding the tube D, beneath the convex under surface of the top of the screw-socket b, and snugly fitting the latter, is the usual felt straining pad d, through which the gas generated in the carbid chamber is obliged to pass on its way to the pipe c and 90 burner tip C. The pad d is held in place by a felt-holder E, which is slipped over the tube D from its lower end and pressed up against the pad, and which is so formed as to engage the tube D with sufficient friction 95 100 to cause it to yieldingly maintain its position when pressed upward against the pad d, to hold the latter in place.

The foregoing provisions relating to the screw-connection between the carbid cham- 110

ber and water reservoir, the felt pad and holder, and the gas-pipe communicating with the burner tip, are of a form common in the type of lamp in which I have illustrated my invention in the accompanying drawings.

A short distance above the point at which it passes through the bottom of the water reservoir (*i. e.* through the center of the top 10 of the screw-socket *b* which forms the bottom of the reservoir at that point,) the tube *D* is provided with one or more holes *e*, Figs. 3, 4 and 5, while the portion of the tube immediately beneath said holes is internally threaded, at *f*. Beneath this 15 threaded portion the tube has its opposite sides cut away, to form extended vertical openings *g*, leaving narrow depending arms or strips *h* at its opposite sides, between said 20 openings, which are joined at their lower ends to the bottom of the tube. The latter is substantially closed, and is shaped to receive and hold a conical valve-seat *F*, which in the present instance is shown as consisting 25 of a double cone, the upper half of which forms the valve-seat and the lower half of which fits in a correspondingly shaped seat formed for it in the bottom of the tube *D*, to which seat it is soldered or 30 otherwise secured.

Fitting within and extending lengthwise through the tube *D* is a rod *G*, whose upper portion, *i*, above the holes *e* in the tube *D*, is preferably of a size to snugly fit the 35 interior of the tube. Below the portion *i*, and opposite the openings *e* in the tube *D*, the rod *G* is reduced in diameter, at *j*, Fig. 6, and below this reduced portion the rod is externally threaded for a considerable portion 40 of its length, at *k*, this threaded portion of the rod coöperating with the internal threads *f* of the tube *D* below the holes *e* in the latter, Fig. 2. The rod *G* is centrally bored from its lower end upward to a point 45 above the threads *k*, and this central bore *l* of the rod communicates at its upper end, by one or more radial openings *m*, with the annular space formed by the externally reduced portion *j* of the rod, and through the 50 openings *e* in the tube *D* with the interior of the water-reservoir.

The lower end of the rod *G*, around the central bore therein, is suitably shaped to snugly fit and coöperate as a valve with the 55 conical valve-seat *F* supported by the lower end of the tube *D*. The central bore *l* in the lower half or portion of the rod *G* constitutes a water-tube of that portion of the rod, while the entire rod constitutes a valve-stem 60 for the valve formed in its lower end. For the purpose of turning the rod to different positions, to correspondingly raise and lower its lower end, and enable the latter to coöperate as a valve with the valve-seat *F*, the 65 upper end of the rod *G* is extended slightly

above the upper end of its inclosing tube *D* and the top of the water reservoir, and has secured to it an operating arm or lever *H*, having a reversely bent outer end adapted to coöperate as a spring-detent with a 70 semi-circular series of notches and projections *n* formed upon the upper surface of the water reservoir, by means of which the rod may be turned to different positions and be yieldingly held therein. 75

The water reservoir is filled through an opening in its top, adapted to be closed by the usual hinged closure *I*. Secured upon one end of the reservoir is the usual hook *J*, for attaching the lamp to the miner's cap, 80 and a pair of laterally extending spring-arms *K* to bear against the front of the cap and prevent sidewise swinging of the lamp, as usual. To the opposite end of the reservoir is secured the reflector *L*. 85

The operation is as follows: When the rod *G* is turned by means of its handle or lever *H* until its lower end is seated tightly against the valve-seat *F* carried by the lower end of the tube *D*, the flow of water from the water 90 reservoir to the carbide chamber is cut off. By turning the rod forward from this position the valve may be gradually opened to any extent desired, and the flow of water be regulated and controlled as required. In the 95 position of the parts shown in Figs. 1, 2 and 3, with the operating handle or lever *H* parallel with the axis of the water reservoir and burner tip, the valve is opened about halfway between closed and full-open position. 100

The cutaway portions *g* of the opposite sides of the lower ends of the tube *D*, which expose the lower portion of the rod *G*, permit the slaked carbide which forms around the lower end of the rod and tube to come in contact with the rod, and adhere more or less thereto, with the result that if the slaked carbide becomes compacted around the lower end of the rod and tube to such an extent as 105 to obstruct the flow of water through or from the open or partly opened valve a slight turning of the rod, either back and forth or in one direction only, will break the adherence of the slaked carbide to the surface of the rod and produce cracks or openings in the mass of carbide surrounding the lower end of the rod and tube, and thereby 110 permit a freer flow of water to be resumed. 115

The size, shape and number of the openings in the lower end of the tube *D* is not material to the accomplishment of the purpose above described, but I have found the long vertical openings *g* in the opposite sides of the tube to be efficient and desirable, since 120 they afford ample exposure of the rod to the surrounding carbide, and at the same time the narrow depending portions *h* of the walls of the tube, between said openings, afford a suitable and firm support for the 125 130

valve-seat F with which the lower end of the rod co-operates, and serve to hold the rod and valve-seat in such relation to each other that the lower end of the rod will always 5 accurately engage the valve-seat. Inasmuch, however, as the principal function which the narrow depending portions *h* of the walls of the tube perform in this respect is to afford a support for the valve-seat F beneath and in axial line with the lower end of the rod G, any other suitable form of support for the valve-seat, performing the same function, may be employed without departing from the broader scope of my invention.

It will be of course understood that no water can pass from the water reservoir to the carbid chamber except through the radial holes *m* and connecting central bore *l* 20 of the rod G, so that when the lower end of the rod is seated upon the valve-seat F the flow of water from the water reservoir to the carbid chamber is entirely cut off. The threaded engagement of the portion *k* of the 25 rod G, beneath the openings *m* therein, with the internally threaded portion *f* of the tube D prevents any downward passage of water externally of the rod G, between it and the surrounding tube D, while the snug fit of the 30 upper half or portion of the rod G in the surrounding portion of the tube D, above the holes *e* in the latter, prevents any water from passing upward around the rod G and escaping from the top of the tube D.

It is manifest that the relative positions of the smooth and threaded portions *i* and *k* of the rod G, and likewise of the internal smooth and threaded portions of the surrounding tube D, may be reversed, with the 40 same result, the threaded portions of the rod and tube being located above the openings communicating with the interior of the water reservoir near the bottom of the latter, and the smooth portions of the rod and tube being located beneath the said openings. In 45 the latter event, the smooth lower portion of the rod G would snugly fit the interior of the lower portion of the tube D, as does the upper half of the rod in the construction illustrated in the drawings, and prevent any 50 passage of water from the water reservoir to the carbid chamber externally of the rod G, between it and the surrounding tube D.

As will be also understood, the primary 55 function performed by the portion of the rod G above the openings communicating with the interior of the reservoir is merely that of a valve-stem, and while the construction shown, in which the tube D extends vertically through the water reservoir (as well 60 as projecting below the same into the carbid chamber), and in which the upper portion of the rod G is of such a size as to snugly fit such upper portion of the tube D, is a desirable one from both a manufacturing and op-

erating standpoint, nevertheless the function performed by the upper half of the rod G as a valve-stem might be performed by any other suitable valve-stem connected with the lower half or portion of the rod G and extending upward through the top of the water reservoir, and the portion of the tube D above the bottom of the water reservoir be omitted. In this event the portion of the tube D below the water reservoir, and the 75 portion of the rod G inclosed therein, would continue to perform the same functions, in substantially the same way, as in the construction disclosed in the drawings.

Having thus fully described my invention, 80 I claim:

1. In an acetylene lamp, the combination, with the carbid chamber and superimposed water reservoir, of a water tube extending from the water reservoir into the carbid 85 chamber in contact with the carbid therein and having its lower end formed to operate as a valve, a valve-seat suitably supported beneath and in axial line with the lower end of the water tube, and means for raising and 90 lowering the water tube to cause its lower end to coöperate as a valve with said valve-seat; substantially described.

2. In an acetylene lamp, the combination, with the carbid chamber and superimposed 95 water reservoir, of a water tube extending from the water reservoir into the carbid chamber in contact with the carbid therein and having threaded engagement with a fixed part of the lamp, to cause the turning 100 of the water tube to raise and lower it, a valve-seat suitably supported in the carbid chamber to coöperate with the lower end of the water tube, and means external to the lamp for turning the water tube; substantially 105 described.

3. In an acetylene lamp, the combination, with the carbid chamber and superimposed water reservoir, of a water tube extending from the water reservoir into the carbid 110 chamber in contact with the carbid therein and having an externally threaded portion beneath the water reservoir, a second tube or casing surrounding the water tube beneath the water reservoir and having an internally 115 threaded portion engaging the external threads upon the water tube, a valve-seat supported by said external tube or casing beneath and in axial line with the lower end of the water tube, and means external to the 120 lamp for turning the water tube and causing its lower end to coöperate as a valve with said valve-seat; substantially described.

4. In an acetylene lamp, the combination, with the carbid chamber and superimposed 125 water reservoir, of a water tube extending from the water reservoir into the carbid chamber and having an externally threaded portion beneath the water reservoir, a second tube or casing surrounding the water 130

with one or more openings communicating with the interior of the water reservoir near the bottom of the latter, and being internally threaded below said openings, and being also provided with one or more openings below its internally threaded portion, a valve-seat carried by the lower end of said tube, a rod extending lengthwise through said tube and having an upper portion snugly fitting the interior of the tube above the upper openings therein and an externally threaded portion engaging the internally threaded portion of said tube, said rod being exposed to the carbid in the carbid chamber through the lower openings in the surrounding tube and being provided with a central bore extending upward from its lower end and communicating at its upper end, through the openings in the surrounding tube, with the interior of the water reservoir, and means external to the lamp for turning said rod to cause its lower end to coöperate as a valve with the valve-seat carried by the lower end of the surrounding tube; substantially described.

10. In an acetylene lamp, the combination, with the carbid chamber and superimposed water reservoir, of a tube or casing secured at its upper end in the top of the water reservoir and extending downward through the bottom thereof and projecting into the carbid chamber, said tube being pro-

vided with one or more openings communicating with the interior of the water reservoir near the bottom of the latter, and being internally threaded below said openings, and having its opposite sides, below its internally threaded portion, cut away to form extended vertical openings, a valve-seat carried by the lower end of said tube below said openings, a rod extending lengthwise through said tube and having an upper portion snugly fitting the interior of the tube above the first mentioned openings therein, and a reduced portion below such upper portion, and an externally threaded portion below said reduced portion engaging the internally threaded portion of the surrounding tube, said rod being also provided with a central bore extending upward from its lower end and communicating at its upper end with the annular space formed by the reduced portion of the rod above its threaded portion, and further communicating, through the openings in the surrounding tube, with the interior of the water reservoir, and means external to the lamp for turning said rod to cause its lower end to coöperate as a valve with the valve-seat carried by the lower end of the surrounding tube; substantially described.

AUGIE L. HANSEN.
